UNITED STATES PATENT OFFICE

119,065

DESIGN FOR A WRINGER

James J. Gough, Chicago, Ill., assignor to Chicago
Electric Manufacturing Company, Chicago, Ill.,
a corporation of Illinois

Application August 7, 1939, Serial No. 86,502

Term of patent 7 years

To all whom it may concern:

Be it known that I, James J. Gough, a citizen of the United States, residing at Chicago, in the county of Cook and State of Illinois, have invented a new, original, and ornamental Design for a Wringer, of which the following is a specification, reference being had to the accompanying drawing, forming part thereof.

In the drawing:

Fig. 1 is a side elevational view of a wringer, showing my new design, with the major portion of the handle broken away, for convenience of illustration, the opposite side of the wringer being a counterpart of the illustrated one.

Fig. 2 is a plan view of the same.

Fig. 3 is an end view of the same, taken from the left-hand side of Fig. 1.

Fig. 4 is a side elevational view of the complete handle, which handle was shown partly broken away, for convenience of illustration, in Fig. 1.

The dominant features of my design reside in the portions shown in full lines.

I claim:

The ornamental design for a wringer, substantially as shown and described.

JAMES J. GOUGH.
